UNITED STATES PATENT OFFICE.

OTTO H. ERICKSON, OF MINNEAPOLIS, MINNESOTA.

ARTIFICIAL LEG.

1,303,645.

Specification of Letters Patent. Patented May 13, 1919.

Application filed December 9, 1918. Serial No. 265,848.

To all whom it may concern:

Be it known that I, OTTO H. ERICKSON, a citizen of the United States, residing at Minneapolis, in the county of Hennepin 5 and State of Minnesota, have invented certain new and useful Improvements in Artificial Legs; and I do hereby declare the following to be a full, clear, and exact description of the invention, such as will enable 10 others skilled in the art to which it appertains to make and use the same.

My invention relates to artificial legs and is particularly directed to the improvement of the construction and operation of artificial legs for lower leg or shank amputations. 15 To the above ends, generally stated, the invention consists of the novel devices and combinations of devices hereinafter described and defined in the claims.

20 In the accompanying drawings which illustrate the invention, like characters indicate like parts throughout the several views.

Referring to the drawings,

25 Figure 1 is a side elevation showing the improved artificial leg;

Fig. 2 is a fragmentary view on an enlarged scale chiefly in vertical section on the line 2—2 of Fig. 1, but with some parts shown in full;

30 Fig. 3 is a plan view of one of the so-called lower end strap hooks;

Fig. 4 is an inner face elevation of the clips shown in Fig. 3;

Fig. 5 is a fragmentary section taken on 35 the line 5—5 of Fig. 2; and Fig. 1^a is a view partly in side elevation and partly in vertical section illustrating the modified form of the leg wherein lower portions of the lower hanger straps are omitted.

40 Of the parts of the leg, the numeral 6 indicates the shank or lower edge section, the numeral 7 the foot which is pivotally connected to the lower end of the shank 6 by a hinge bolt 8; the numeral 9 the slip socket which works 45 telescopically in the upper end of the shank 6 and has a shoulder 10 engageable as a stop with the upper edge of said shank; and the numeral 11 indicates the so-called lacer, which latter is applied around the thigh of 50 the wearer in the customary way, being usually laced in front.

It is customary to connect the lacer and the shank by so-called hinge straps and this I do in my improved leg in a novel and 55 improved manner. The upper hinge straps 12 are secured to the sides of the lacer 11

in the customary way and are pivotally connected by screws 13, or similar devices, to the upper ends of the lower hinge straps 14. 60 These lower hinge straps 14 are riveted to the sides of the shank 6 and, as one novel feature of this invention, are extended downward along the sides of the shank and their lower ends are pivoted on the bolt or 65 pivotal connection 8 between the shank and foot. In this way, the load from the weight of the wearer is distributed through the entire shank and is carried down to the foot through the angle joint 8. This is highly 70 important when the leg is made for heavy persons and where, of course, extra strength is desired in the leg. It is also important in any leg structure because it reinforces the shank, permits the same to be made of lighter 75 material than would otherwise be possible, and moreover, prevents shrinkage or variation in the length of the leg.

In the upper portions, the hinge straps 14 are expanded and formed with long wide 80 slots 14^a which give the said straps, near their upper ends, an endless loop formation with parallel sides. In line with the slots 14^a of the straps 14, shank 6 is formed in its sides with vertical slots 6^a that correspond 85 in size, preferably to the slots 14^a. The slip socket 9 is preferably extended down in the shank approximately as far as the lower extremities of the slots 6^a and 14^a and, at their lower side portions are provided with rigidly 90 secured anchoring hooks 15, preferably formed of flat spring steel riveted to the shank, and at their upper ends provided with flat outstanding hooks that are adapted to detachably engage the upturned hook flange 95 16 of floating joint hooks 17. These so-called floating hooks 17 are preferably made from flat spring steel and at their outer upper edges are formed with slots 18 through which the lower end portions of heavy elastic straps 19 are passed. These elastic straps 19 work in the slots 14^a and are preferably nearly as wide as the said slots, and at their upper ends they are lapped through slots in the lower ends of small anchoring plates or 100 clips 20, which, by means of screws 21 are secured to the upper portions of the straps 14 just above the upper extremities of their slots 14^a. To provide for vertical adjustments of the elastic straps 19, the clips 20 are 105 provided with a plurality of vertically spaced holes 22, through any one of which the screws 21 may be passed. This affords 110

an extremely simple means of independently and vertically adjusting the elastic hinge straps which, of course, yieldingly support the socket 9 within the shank. The shank 9, 5 as is customary, is provided in its sides with channels 9^a that engage the upper end portions of the straps 14 and hold the socket against rotation.

It should be further noted that the up- 10 turned hook flange 16 of the floating hook 17, at its ends, is extended, as best shown in Figs. 3, 4 and 5, so that they project beyond the sides of the slots 6^a and work frictionally against the inner surfaces of 15 the shank 6, thereby affording wearing and guiding surfaces for the lower portion of the socket. Inasmuch as the shank 6 will be made of nonmetallic substance, such, for example, as raw hide, wood, or fiber board, 20 the frictional movement of the ends of the flange 16 against the said shank will produce very little friction and no noise.

The pivotal connection at 13 between the joint straps 12 and 14, of course, affords the 25 knee pivot or joint of the artificial leg. The looped upper end portions of the straps 14 so reinforce the upper portion of the shank 6 that said shank may be slotted in the connection of the clips 15 and 17 therethrough 30 and still the said shank may be brought to the top of the loop, and thus made of full length. The full length shank gives the best kind of a guide for the slip socket and gives the best possible form of leg. In this 35 way, also, the slip socket is connected to the elastic suspending strap through slots in the shank as well as through slots in the lower hinge straps. The elastic straps, because of their flat formation are advisably 40 employed rather than coiled springs, but in a broad sense, the said elastic straps are springs. It will be further noted that the channels 9^a in the sides of the slip socket, 45 while permitting axial movements thereof, hold the same against rotation, and in such positions that when forced downward to position, the hooks 15 will be alined with the grooves 6^a for proper engagement with the floating hooks 16-17. As the upper and 50 outer portions 17 of the said floating hooks work in the slots 14^a, they are then, of course, held interlocked with the hooks 15 and against edgewise displacement.

The construction described, while highly 55 efficient, is cheap to make, strong and durable, and moreover, capable of easy repairs. The elastic straps 19, for instance, if worn out, may be very easily and quickly replaced.

In the modified construction illustrated in 60 Fig. 1^a, the lower portions of the hinge strap 14 are omitted, but the said lower straps herein designated by 14^b are, nevertheless, provided with loops that completely surround the slots 14^a, thereby reinforcing the 65 upper portion of the shank partly around

the slots thereof. The same novel arrangement of the elastic straps and suspending hooks and clips described in connection with Figs. 1 to 5, inclusive, would be employed in the modified form of Fig. 1^a.

70

What I claim is:

1. In an artificial leg, the combination with a shank equipped with a foot at its lower end and provided in its sides near its upper end with longitudinal slots, of a lacer having upper hinge straps depending from its sides, lower hinge straps secured to the sides of said shank and pivotally connected to said upper hinge straps, a slip socket working in the upper end of said shank, and springs anchored to the sides of said shank in the vicinity of the upper portions of said slots and connected to said shank through these slots.

2. In an artificial leg, the combination with a shank and a lacer, of pivotally connected upper and lower hinge straps secured to the sides, respectively, of said lacer and shank, said hinge straps and the sides of said shank having alined slots, the slots of said shank being completely surrounded and reinforced by an integral loop-like portion of said lower hinge straps, a slip socket telescoped into said shank and having hooks alined with said slots, springs alined with 90 said slots anchored at their upper ends to said lower hinge straps and provided at their lower ends with hooks for detachable interlocking engagement with the hooks of said socket.

95

3. In an artificial leg, the combination with a shank and a lacer, of pivotally connected upper and lower hinge straps secured to the sides, respectively, of said lacer and shank, said hinge straps and the sides of said shank having alined slots, the slots of said shank being surrounded and reinforced by said lower hinge straps, a slip socket telescoped into said shank and having hooks alined with said slots, springs alined with 105 said slots anchored at their upper ends to said lower hinge straps and provided at their lower ends with hooks for detachable interlocking engagement with the hooks of said socket, the connection between the upper ends of said springs and said lower straps including anchoring clips, and means for adjusting the same vertically in respect to said straps.

110

4. In an artificial leg, the combination with a shank and a lacer, of pivotally connected upper and lower hinge straps secured to the sides, respectively, of said lacer and shank, said hinge straps and the sides of said shank having alined slots, the slots of said shank being surrounded and reinforced by said lower hinge straps, a slip socket telescoped into said shank and having hooks alined with said slots, springs alined with 120 said slots anchored at their upper ends to 125 said lower hinge straps, a slip socket telescoped into said shank and having hooks alined with said slots, springs alined with 130 said slots anchored at their upper ends to

said lower hinge straps and provided at their lower end with hooks for detachable interlocking engagement with the hooks of said socket, the hooks on the lower ends of said 5 springs having extended portions that overlap the edges of the slots in said shank and work between said shank and slip socket.

In testimony whereof I affix my signature in presence of two witnesses.

OTTO H. ERICKSON.
